L. MOLLART

STOCK CUTTING MACHINE

Filed March 23, 1923

Patented Sept. 2, 1924.

1,507,503

UNITED STATES PATENT OFFICE.

LOBEGOTT MOLLART, OF WATERTOWN, WISCONSIN.

STOCK-CUTTING MACHINE.

Application filed March 23, 1923. Serial No. 627,121.

To all whom it may concern:

Be it known that I, LOBEGOTT MOLLART, a citizen of the United States, and resident of Watertown, in the county of Jefferson and

5 State of Wisconsin, have invented certain new and useful Improvements in Stock-Cutting Machines; and I do hereby declare that the following is a full, clear, and exact description thereof.

10 This invention relates to stock cutting machines and is particularly directed to a machine for cutting rubber stock.

Machines as heretofore constructed for cutting the rubber stock furnished rubber heel manufacturers have not been wholly satisfactory as they distorted the stock and made an irregular slanting or tearing cut; obviously, therefore, the resulting slice of stock was uneven and irregular and not suited for the purpose intended.

15 This invention is designed to overcome the above noted defects, and objects of such invention are, therefore, to provide a machine which will cut relatively soft stock in an

20 even and smooth manner which will not distort the stock during the cutting operation, which may be adjusted to accurately cut the exact thickness required, which is easy to operate, and which makes a cut by a shearing

25 stroke.

Further objects are to provide a machine for cutting rubber stock which is extremely simple in construction, which may be readily produced, which is equipped with a knife, a 30 portion only of which may be used for a given period, and which may thereafter be shifted to present a fresh or sharp surface, and which is so constructed that the knife may be readily removed and re-sharpened.

35 An embodiment of the invention is shown in the accompanying drawings, in which:—

Figure 1 is a sectional elevation of the machine such view corresponding roughly to a section on a line 1—1 of Figure 2.

40 Figure 2 is a plan view of the machine.

The machine comprises a base 1 to which a pair of curved brackets 2 are bolted. A transverse shaft 3 is journaled in these brackets and projects at each end beyond

45 such brackets as may be seen from Figure 2. This shaft is provided with a circular knife 4 which is rigidly clamped by means of a nut 5 in relatively fixed position to the shaft 3.

50 A lever is rigidly secured to the shaft 3 and is provided with an upstanding relatively long arm 6 terminating in a handle 7

and with a downwardly projecting arm 8. A counter balance 9 is adjustably mounted upon a downwardly projecting arm 10 having a hub 26 rigidly secured to the shaft 3 and extending through an aperture 27 in the base or bed plate 1.

55 A carrier for the stock is provided, and is equipped with a trough-like holder 11 for the stock 12. This holder is carried by a pair of links or arms 13 which are in turn joined and braced by a transversely extending channel member 14 as may be seen from Figure 1. The outer ends of the arms 13 are carried by means of rollers 15 mounted upon a transverse shaft 16 journaled in such arms. These rollers are adapted to travel across the upper smooth surface of the bed plate 1 when the lever 6 is operated. The other ends of the arms 13 are pivotally joined to the downwardly projecting extension 8 of the lever and to a corresponding lever 17 rigidly carried by the left hand end of the transverse operating shaft 3 as shown in Figure 2.

60 The outer end of the right hand arm or link 13 has pivotally joined thereto a bracket 18 which is yieldingly pressed by means of a spring 19, (see Figure 2). This bracket carries a supporting arm 20 which is rigidly attached thereto and is adapted to bear against the outer face of the circular knife 4 as may be seen from Figure 2. It is contoured to correspond to the trough 11 and is adapted to support the projecting end of the stock during the cutting operation. An adjustable limit 21 is provided for the arm 20 to hold such arm 20 in slightly spaced relation when not in contact with the knife 4. This limiting device may conveniently be a bolt or screw as shown suitably equipped with a lock nut.

65 A bracket 22 is rigidly secured to the right hand face of the base or bed plate and adjustably receives the threaded spindle 23 of a gauge plate 24 against which the stock is adapted to abut. The outer end of the spindle 23 may be conveniently provided with handwheel 25 to facilitate adjustment. The bracket 22, as may be seen from Figure 1, is slotted and is bolted through this slot to the bed plate to provide the necessary adjustment for varying sizes of stock.

70 The operation of the apparatus is as follows:—The stock is placed in the trough 11 as shown, and the operator shoves the stock towards the right into contact with the

2
gauge plate or stop 24 and grips the handle 7 with his right hand. He then rocks the lever 6 until its center line occupies the position shown by the imaginary line in Figure 5 1. This, it will be noted, gives the rotary knife 4 a one-eighth turn. While the knife is executing this movement, the carrier is drawn inwardly towards the knife thereby presenting the stock to the knife and allowing 10 it to be subjected to a shearing cut.

The stock, it will be noted, is relatively soft and easily distorted and, therefore, the slanting shearing cut is highly desirable. In addition to this, the smoothness 15 of the cut is further insured by the relatively narrow support immediately adjacent the outer face of the knife. This support, together with the support or trough 11 furnishes the necessary support for the soft 20 stock immediately adjacent the knife and on opposite sides thereof, so as to eliminate distortion. It is further apparent that when the cut has been completed the carrier will have moved its greatest distance inwardly 25 and the cut portion of the stock will be clear of the stop or gauge plate 24 and consequently will freely fall from the machine.

When the active portion of the knife has been dulled by a large number of operations, the nut 5 may be loosened and the 30 knife may be given a partial turn to present a fresh surface. Obviously the knife is turned in the same direction at each adjustment so as to continuously present new 35 surfaces until the entire edge of the knife has been utilized. When the entire edge of the knife has become dull, the knife may be readily removed from the shaft 3 and resharpened in an extremely simple and 40 easy manner.

It is to be noted that the weight 9 acts 45 as a pendulum and when the operator is continuously oscillating the lever 6, the weight stores a certain amount of energy and aids in the periodic swinging of the lever and actuation of the knife. In fact in 50 actual practice it has been found that a man may readily operate this machine in an extremely rapid and easy manner and that the severed material is uniform and has accurately parallel smooth faces.

This soft rubber stock, after it has been sliced into these relatively smaller portions, is designed for use in the production of 55 rubber heels and similar articles and as is well known it is desirable that the utmost accuracy in the cutting of these portions be maintained.

It will be seen, therefore, that a machine 60 has been provided which will rapidly and accurately cut soft and easily distorted stock, which may be most readily manipulated, and which is adjustable to present fresh knife surfaces for the active portions.

65 It is, of course, obvious that a power

drive may be readily applied to a machine of this type and that other variations may be made. It is, therefore, intended that although the invention has been described in considerable detail, it is not to be limited except as defined in the appended claims.

I claim:

1. A stock cutting machine comprising a circular knife, a lever for rotating said knife back and forth through a portion of a turn, a carrier for supporting the stock closely adjacent the knife, and mechanism operatively coupling said carrier and knife to reciprocate said carrier as said knife is oscillated, whereby said stock is presented to said knife while said knife is being oscillated.

2. A stock cutting machine comprising a revolvably mounted knife, a lever for rotating said knife back and forth through a portion of a turn, a reciprocatory carrier having a trough-like portion for supporting said stock, link mechanism connecting said lever and carrier and adapted to reciprocate said carrier to present said stock to said knife, and a support spaced from the end of said trough-like portion for supporting the projecting portion of said stock, whereby said stock is supported upon opposite sides of said knife while it is being cut.

3. A stock cutting machine comprising a bed plate, a transverse shaft supported therefrom, a circular knife adjustably mounted upon said shaft, a lever rigidly mounted upon said shaft and having an operating handle at one end, a counter-weight carried by said shaft and extended radially downwardly therefrom, a reciprocatory carrier mounted upon the upper side of said bed plate and having an elongated support for said stock, and link mechanism connecting the forward portion of said carrier with said shaft, whereby when said knife is rocked through a portion of a turn of said lever said carrier is advanced towards said knife.

4. A machine for cutting elongated rubber stock comprising a bed plate, a transversing operating shaft carried by said bed plate, an operating lever rigidly attached to said shaft and terminating in an operating handle, a pair of relatively short levers projecting downwardly from said shaft, a carrier including a pair of members whose forward ends are pivotally joined to said pair of levers, means for supporting the other end of said members from said bed plate, a support projecting beyond said carrier and adapted to support the projecting portion of the rubber stock, a circular knife adjustably mounted upon said transverse shaft and adapted to be spaced between said carrier and said support, resilient means for yieldingly urging said support into contact with the outer face of said circular knife.

5. A machine for cutting elongated rubber stock comprising a carrier including a pair of arms, a trough-like member carried by said arms, a support conforming to said 5 trough-like member and spaced from the outer end thereof a slight distance, an adjustable stop supported from a stationary portion of said machine and adapted to align with said trough-like member in one 10 position of the latter, a transverse operating shaft paralleling said trough-like mem-

ber, a circular knife secured thereto, an operating lever rigidly attached to said shaft, a pair of shorter levers rigidly attached to said shaft and pivotally joined to said arms, 15 and a downwardly extending counter-weight rigidly carried by said shaft.

In testimony that I claim the foregoing I have hereunto set my hand at Watertown, in the county of Jefferson and State of Wisconsin. 20

LOBEGOTT MOLLART.
